Robert F. West, West Simsbury, and Laird F. Covey, Easton, Conn., assignors to The Stanley Works, New Britain, Conn.

Filed May 3, 1971, Ser. No. 140,006

Term of patent 14 years

Int. Cl. D8—03

U.S. Cl. D8—97

FIG. 1 is a perspective view of a handsaw showing our new design;

FIG. 2 is an elevational view of the right side thereof as seen in FIG. 1 and drawn to a diminished scale;

FIG. 3 is a top view thereof drawn to the scale of FIG. 2;

FIG. 4 is a bottom view thereof drawn to the scale of FIG. 2;

FIG. 5 is an elevational view of the left side thereof as seen in FIG. 1 and drawn to the scale of FIG. 2;

FIG. 6 is a front view thereof;

FIG. 7 is a rear view thereof;

FIG. 8 is a sectional view thereof along the line 8—8 of FIG. 2 drawn to an enlarged scale and illustrating the external contour of the handle portion thereat and the configuration of the end of the passageway exposed at the front end of the handle portion;

FIG. 9 is a similar sectional view thereof along the line 9—9 of FIG. 2, drawn to an enlarged scale, and illustrating the external contour of the handle portion thereat and the configuration of the end of the passageway exposed at the rear end of the handle portion; and

FIG. 10 is a side elevational view thereof similar to FIG. 2 with the blade in a more fully extended position.

It is understood that the incomplete showing of detail in FIGS. 1, 2, 5 and 10 represents a continuation of that detail along the length indicated.

We claim:

The ornamental design for a handsaw, as shown and described.
